GARBAGE CAN

Leo B. Couch, Maplewood, Mo.

Application July 19, 1937, Serial No. 154,364

3 Claims. (CL 220—87)

My invention relates to a new and useful improvement in garbage cans, and has for its principal object to produce a garbage can in which the odors usually emanating therefrom are counteracted or neutralized. Another object of my invention is to produce a garbage can in which the deodorizing apparatus is relatively simple, and is to be attached, preferably, to the cover of the garbage can, such attachment being readily accomplished. By destroying the odors that usually emanate from a garbage can I also keep down the insect pests which generally assemble around garbage pails.

Fig. 1 is a top plan view of my improved garbage can with the handle for the cover partly broken away.

Fig. 2 is a side elevation, partly in section, of my improved garbage can.

Fig. 3 is a top plan view, partly in section, taken on the line 3—3, Fig. 2, looking in the direction of the arrows.

Fig. 4 is an enlarged, detail, sectional view taken on line 4—4, Fig. 1.

In the drawing, the garbage can, of usual construction, is designated by the numeral 10 and is provided with a bail handle 11 secured thereto. The cover 12 is formed in the usual manner, with a flange 13 at its circumference adapted to fit about the upper portion of the garbage can 10. The cover 12 is provided with the usual handle 14 whereby said cover may be manipulated.

In the center of the cover 10 I provide a circular depression 15, and in the center of said depression 15 I provide a circular opening 16 about 1½ inches in diameter. The circular depression 15 is about $\frac{1}{8}$ inch in depth. The opening 16 provides an outlet for deodorized gases from the garbage pail, as well as serving as an opening for replenishing the deodorant, either liquid or solid, to be hereinafter referred to. The circular depression 15 also facilitates the pouring of water or other liquid into a container, within the garbage pail, to be hereinafter described.

Attached to the under surface of the cover 12 is a container 17, preferably by welding. For the average size garbage can the container 17 is usually circular in form and about 6 inches in diameter and about 2 inches deep. The wall of the container 17 is imperforate except near the upper portion thereof, where a series of circular openings 18 is provided. These openings are $\frac{1}{8}$ inch in diameter, are equally spaced apart, and are $\frac{1}{8}$ inch below the under surface of the cover, and they are twelve in number.

Adjacent the inner surface of the wall of the

container 17 is a copper wire screen 19, to one side of which is secured a fabric mesh 20, preferably by stitches 21 at the top of the container 17, as shown in Figs. 2 and 4, although such stitches can of course also be placed at the bottom of the container if preferred. The combined copper screen 19 and fabric mesh 20 extend from the floor of the container 17 to the top of said container. The copper screen 19 and fabric mesh 20 combine to form a member A, 10 which member rather closely engages the inner wall of the container 17 and serves to screen the gases arising from the garbage as such gases pass through the member A. As the member A is closely adjacent to the openings 18 in the upper portion of the container 17, gases accumulating in the garbage can 10 are drawn through the openings 18 into contact with the member A, and thereby are subjected to the deodorant carried up by capillary attraction by the fabric mesh 20, which has its lower portion immersed in a liquid 22 in the container 17, which liquid contains a deodorant suitable for the purpose of deodorizing said gases. The result is that when the deodorized gases passed through the screen 25 get into the upper portion of the container 17 and escape through the perforation 16, such gases are no longer obnoxious.

It has been my experience that as fast as the gases in the garbage can 10 are formed, they 30 are immediately drawn into the container 17 through the openings 18 and subjected to the deodorant 22 carried by capillary attraction by the screen A.

By actual experience I have found that a deodorant need only to be renewed about every ten days, and that a small amount of water, about a cupful, need be supplied every two or three days, which keeps my improved garbage can thoroughly deodorized.

As the gases form in the garbage can they can only escape through the openings 18 in the container 17, induced by the central opening 16, which acts as a flue, in the cover 12, and as all such gases must pass through the deodorant- 45 impregnated screen A, such gases are effectively denuded of their offensive odors.

I claim:

1. A garbage can provided with a cover therefor, said cover having a centrally located aperture therein, a container on the inner side of the cover and carried thereby and surrounding said centrally located aperture in said cover and in open communication therewith, and a screen surrounding the inner periphery of said con- 55

tainer, said screen comprising a metallic mesh and a fabric material secured against said metallic mesh, said container being provided with a series of apertures adjacent the top portion of said container whereby gases accumulating in said garbage can may escape from said garbage can, said fabric material being impregnated with a deodorizing solution.

2. A garbage can provided with a cover therefor, said cover having a centrally located aperture therein, a container on the inner side of the cover and carried thereby and surrounding said centrally located aperture in said cover and in open communication therewith, and a screen surrounding the inner periphery of said container, said screen comprising a metallic mesh and a fabric material secured against said metallic mesh, said container being provided with a series of apertures adjacent the top portion of said container whereby gases accumulating in said garbage can may escape from said garbage can, said

fabric material being impregnated with a deodorizing solution, and said screen being positioned against the inner, vertical surface of said container.

3. A garbage can provided with a cover therefor, said cover having a centrally located aperture therein, a container on the inner side of the cover and carried thereby and surrounding said centrally located aperture in said cover and in open communication therewith, said container being provided with a series of circumferential openings through the upper portion of the vertical wall thereof, and a screen and a fabric material attached to said screen surrounding the inner periphery of said container, said container being provided with a series of apertures adjacent the top portion of said container whereby gases accumulating in said garbage can may escape from said garbage can, said fabric material being impregnated with a deodorizing solution. 5 10 15 20
